E. C. RICHARD

PISTON

Filed March 29, 1922

Inventor

Eugene C. Richard

By his Attorney

Blackmores, Spencer & Flint.

UNITED STATES PATENT OFFICE.

EUGENE C. RICHARD, OF FLINT, MICHIGAN, ASSIGNOR TO GENERAL MOTORS CORPORATION, OF DETROIT, MICHIGAN, A CORPORATION OF DELAWARE.

PISTON.

Application filed March 29, 1922. Serial No. 547,724.

To all whom it may concern:

Be it known that I, EUGENE C. RICHARD, a citizen of the United States of America, and a resident of Flint, county of Genesee, 5 and State of Michigan, have invented certain new and useful Improvements in Pistons, of which the following is a full, clear, concise, and exact description, such as will enable others skilled in the art to which the 10 invention relates to make and use the same, reference being made therein to the accompanying drawings, which form a part of this specification.

My invention relates to pistons such as 15 are used in single acting engines, air pumps, etc., and especially to pistons designed especially for use in internal combination engines.

The object of my invention is to provide 20 means associated with a piston for preventing sidewise movement thereof within the cylinder in which it operates, which is a phenomenon well known to automobile engineers and one commonly referred to as 25 "piston slap" and is characterized by pounding noises when the engine is in operation; the movement being due to complex variations in magnitude and direction of various forces acting upon the piston, particularly 30 in an internal combustion engine, accentuated by the looseness of the piston within its cylinder necessary in internal combustion engine practice to avoiding "seizing" of the piston within the cylinder under 35 the high temperature conditions present in such engines.

The drawing accompanying and forming 40 a part of this specification illustrates the preferred embodiment of my invention; although it will be appreciated that the invention may take other specific forms, and that the same includes all such variations and modifications of the particular embodiment thereof illustrated and hereinafter described as come within the scope of the concluding claims, wherein the distinguishing features wherein my invention consists are particularly pointed out.

In the drawing:

Figure 1 is a fragmentary sectional view 50 showing an engine cylinder with my improved piston therein in elevation.

Figure 2 is a view showing a section of my improved piston upon a larger scale,

and upon a longitudinal plane at right 55 angles to the piston pin and to the crank shaft of the engine.

Figure 3 is a view showing a section upon a transverse plane at right angles to the path of travel of the piston and located at 60 the piston pin.

Figure 4 is a fragmentary sectional view similar to Fig. 3 but showing a modified form of my invention.

Referring now to the drawing, the reference numeral 4 designates an engine cylinder, 5 the crank shaft and 6 the connecting rod of the engine, all in a conventional manner; the upper end of the connecting rod being connected with the piston 7 70 through and by means of a transversely extending piston pin 8 shown as hollow and the ends of which are supported in bearings provided in the peripheral wall of the piston; all as is usual in internal combustion engine practice. The piston will be provided with the usual packing rings 9, as many as may be deemed necessary or desirable in each particular case.

The piston 7 is provided with a recess or 80 groove 10 in its periphery or cylindrical portion and which groove extends circumferentially about the piston, and is preferably so located that it extends across the openings in the piston wall in which the 85 ends of the piston pin 8 are supported; and the numeral 11 designates a ring located within the groove and which ring is split or divided as indicated at 12.

The peripheral wall or skirt of the piston 90 is provided with a hole at 13 opening into the bottom of the groove, and which hole is illustrated as arranged at approximately 95 ninety degrees (90°) to the axis of the piston pin and at one end of a diametrical line or dimension of the piston; and 14 designates a plunger the outer end of which abuts against the inner surface of the ring 11, and which plunger is forced outward 100 and against the ring by a spring carried by the piston—the result being that the piston is forced bodily sidewise and in a direction substantially at right angles to the axis of the piston pin and against the interior of the cylinder diametrically opposite the plunger 105 14; as the cylinder wall adjacent the point of contact between the end of the plunger and the ring provides a fixed abutment.

against which the spring acts, the piston as a whole being free to move; and the same being in fact moved in the manner aforesaid by the reaction of the spring acting through the plunger and portion of the ring engaged by the free end thereof, against the cylinder wall which provides a fixed abutment or stop for the ring.

The spring aforesaid is preferably U-shaped as shown and comprises a middle portion 15 which is fixedly secured to the inner end of the plunger 14, and side portions 16 having large holes through which the piston pin extends; and whereby the spring 15 and plunger are supported from the piston pin and from the hole in the piston wall through which the outer end of the plunger extends.

The action of the spring to force the piston bodily in a direction at right angles to the axis of the piston pin will obviously occur in all cases wherein the spring is free to act against a relatively loose element carried by piston, and which element is pressed against the cylinder wall by the spring and for which element the cylinder wall provides a fixed abutment; from which it follows that the ring or equivalent abutment member need not of necessity be split, and need not extend throughout the entire circumference of the piston; so long as the abutment member thus provided is loose relative to the piston so that it may be forced outward by the spring and against the adjacent inner wall of the cylinder. The split ring shown, however, is preferable, as it may then be readily introduced into a groove in the piston and acts as a packing element in addition to an element against which the end of the plunger acts in the manner and for the purpose hereinbefore explained. The location of the groove shown secures a construction in which the ring prevents the ends of the piston pin from coming into contact with the interior of the cylinder and scoring the same which, while not in itself a new idea, is a feature of manifest advantage secured in my invention.

The spring member of my invention instead of being flat as shown in Figures 2 and 3 may be in the form of a coiled spring 17 extending through a hole 18 in the cylinder and acting upon the inner surface of the abutment member 19; the inner end of the said spring acting against a stirrup 20 similar in form to the U-shaped spring hereinbefore referred to and similarly supported within the piston, but which need not be resilient as the spring action is provided by the said spring 17 which obviously acts against the member 19 in precisely the same manner as the plunger 14 in the form of my invention first herein described.

Having thus described and explained my

invention, I claim and desire to secure by Letters Patent:

1. In combination with a hollow piston having a transversely extending piston pin, a groove in its peripheral surface extending circumferentially thereof and across the ends of the piston pin, and a hole arranged substantially at right angles to the axis of the piston pin and extending through the piston wall and into the groove aforesaid; a split ring located within said groove; a plunger extending through said hole and engaging the inner surface of said ring; and a U-shaped spring member the sides of which are supported by said piston pin and the middle portion of which is operatively connected with said plunger. 75

2. In combination with a hollow piston having a transversely extending piston pin, a groove in its peripheral surface extending circumferentially thereof, and a hole arranged substantially at right angles to the axis of the piston pin and extending through the piston wall and into the groove aforesaid; a split ring located within said groove; a plunger extending through said hole and engaging the inner surface of said ring; and a spring member supported by said piston pin and operatively connected with said plunger and acting outwardly 95 against said ring through said plunger. 85

3. In combination with a hollow piston having a transversely extending piston pin, a groove in its peripheral surface extending circumferentially thereof, and a hole arranged substantially at right angles to the axis of the piston pin and extending through the piston wall and into the groove aforesaid; a split ring located within said groove; a plunger extending through said hole and engaging the inner surface of said ring; and a spring member located within the piston and acting upon said plunger to force the same outwardly against said ring. 100

4. In combination with a hollow piston having a transversely extending piston pin, a groove in its peripheral surface extending circumferentially thereof, and a hole extending through the piston wall and into the groove aforesaid; a ring located within said groove; and spring operated means located within the piston and acting against said piston pin and through said hole and against said ring. 110

5. In combination with a hollow piston having a transversely extending piston pin, and a groove in its peripheral surface; an abutment member located in said groove; and a spring located within said piston and acting between said piston pin and said abutment member to force said abutment against the interior of a cylinder in which the piston operates; the arrangement of the elements aforesaid being such that pressure applied to said abutment member by said spring reacts 125 130

to force the piston bodily in a direction at right angles to the axis of said piston pin.

6. In combination with a hollow piston having a transversely extending piston pin, ⁵ and a recess in its peripheral surface; an abutment member located in said recess; and a spring acting between said piston pin and said abutment member to force said abutment against the interior of a cylinder in which the piston operates; the arrangement of the elements aforesaid being such that pressure applied to said abutment member reacts to force the piston bodily in a direc-

tion at right angles to the axis of said piston pin. ¹⁵

7. The combination with a hollow piston having a transversely extending piston pin, of means separate from the piston and located within the same, and carried by the piston pin, and acting against the wall of a cylinder in which the piston operates for forcing the piston bodily in a direction at right angles to the axis of the piston pin. ²⁰

In testimony whereof I affix my signature.

EUGENE C. RICHARD.
